(57) **CLAIM**

The ornamental design for smart gel tool handle, as shown and described.

DESCRIPTION

FIG. 1 is a perspective environmental view of the smart gel tool handle.

FIG. 2 is a right side view of the smart gel tool handle of FIG. 1.

FIG. 3 is a front view of the smart gel tool handle of FIG. 1.

FIG. 4 is a top plan view of the smart gel tool handle of FIG. 1.

FIG. 5 is a left side view of the smart gel tool handle of FIG. 1.

FIG. 6 is a bottom plan view of the smart gel tool handle of FIG. 1; and,

FIG. 7 is a rear view of the smart gel tool handle of FIG. 1. The broken lines shown in FIGS. 1-7 are for the purpose of illustrating the environmental structure of the smart gel tool handle and are not part of the claimed design.
